CORE WINDING START DEVICE

Donald J. Balash, Bay City, Mich., assignor to The Dow Chemical Company, Midland, Mich., a corporation of Delaware

Filed May 27, 1963, Ser. No. 283,337

3 Claims. (Cl. 242—19)

This invention relates to a device for use on relatively high speed thread, or fiber winding machines, for starting a fiber winding on a core on such machines.

In the manufacture of certain plastic fibers, threads or microtapes, such as those formed of polypropylene, polyethylene and polymers containing vinylidene chloride, a plurality of fibers, which can be mono-filaments or bundles of mono-filaments, are taken from a final snubber to a winding machine where the fibers are individually wound upon separate cores to form packages of predetermined size. Present winding machines can operate at fiber speeds of up to approximately 1000 feet per minute. However, present machines which operate at such high speeds generally require slow-down or stopping when starting a thread on a core. In the interest of more efficient productivity, it is contemplated to develop winding machines to operate with fiber speeds over 1000 feet per minute, and which will not require machine slow-down or stopping for thread starting on a core. At fiber speeds of even 350 feet per minute, great manual dexterity is required to start a moving fiber upon a core, since the core must be rotating with a surface speed of approximately the same as the moving fiber if bunching, or snarling is to be avoided. Manual core starting operations in a winding machine are impractical, if not almost impossible, at fiber speeds in excess of 400 feet per minute.

The device of the present invention solves the problem of manually starting a core of thread in a winding machine at speeds in excess of 400 feet per minute, in a simple and effective manner. Briefly, the device of the invention is in the form of a thin circular disc, having an abutment means, such as a slot, formed therein. The disc is affixed to the end of the winding spindle for rotation therewith. By a simple thread guiding maneuver, the moving fiber is engaged by the slot of the rotating disc and wrapped about the core on the spindle. Cutting means are arranged whereby the waste end of the fiber may be cut after winding operation commences. The device of the invention is readily adapted to existing winding machines without the need for extensive modification, if at all.

The main object of this invention is to provide a device for use in manually starting a fiber upon a core in a high speed winding machine.

A more specific object is to provide a device for use in manually starting a moving fiber upon a core in a winding machine wherein the fiber is moving in excess of 400 feet per minute, and wherein it is not required to slow down or stop the machine to start a fiber upon a core.

Another object is to provide a device for manually starting a moving fiber upon a core in a winding machine, in a simple and effective manner.

These and further objects and features of the invention will become more apparent from the following description and accompanying drawings wherein:

FIG. 1 is a fragmentary view of a winding machine having a fiber or thread roll starting device illustrative of an embodiment of this invention;

FIG. 2 is an enlarged plan view of the device of FIG. 1;

FIG. 3 is a view as seen from line 3—3 in FIG. 2; and

FIG. 4 is a plan view of a modified embodiment of the device of the invention.

Referring now to the drawings, and more particularly to FIG. 1, numeral 6 identifies a portion of a thread wind-

2

ing machine, which may be of the type manufactured under the label of the Universal Winding Company, of Providence, Rhode Island, and identified as Model No. 955, and which has a plurality of winding spindle assemblies 8. The machine includes means to independently regulate the speed of the spindles 8 and to cause winding of cores, in a desired manner. Since the present invention is concerned primarily with the starting of a fiber on a core, various details of the winding machine will not be discussed other than where necessary for a full understanding of the invention.

The winding machine includes a pressure plate and traversing guide assembly 10 adapted to engage the fiber for proper winding action upon a core. Hanger means 12 are arranged upon the machine for support of a fiber, which comes from a snubber (not shown), and is pulled by an air aspirator (not shown) mounted at the distal end of the row of winder heads. While only one set of hanger means is shown, it is pointed out that there will be as many sets of hanger means as required to serve all the spindles on the winder. A winder compensator arm 14 is arranged for control action of each spindle.

The device of the invention is in the form of a slotted, circular disc 16 which is affixed to the end of a spindle 8. The major diameter of the disc 16 is somewhat less than the inner diameter of a core 18 on which the winding is to take place, so that the core may be slipped axially on or off a spindle 8. Each spindle assembly has a pair of helical springs 20 extending about the spindle and mounted in parallel planes, which springs serve as a resilient support for a core during a winding operation.

The disc 16, as best seen in FIGS. 2 and 3, has an L-shaped slot one leg 22 of which is positioned radially and extends inwardly from the periphery of the disc to a distance of approximately one-quarter the diameter of the disc, the other, or base leg 24 being at a right angle to the first leg and extending in a direction opposite to which the disc will rotate with the spindle. A slot width of $\frac{1}{8}$ inch on a $1\frac{15}{16}$ inch diameter disc, was found to provide satisfactory results. A hole 26 is provided in the center of the disc whereby the disc may be mounted on the spindle and secured thereto by a snap-ring, or washer 28. A blade 30, having a cutting edge 32, is mounted upon the inside of the disc by fastening means in the form of bolt and nut assemblages 34, so that the cutting edge traverses the slot leg 24.

A modified form of disc 36 is shown in FIG. 4, which differs from the disc 16 primarily in the fact that a removable cutter element is eliminated. The disc 36 includes an L-shaped slot one leg 38 of which extends in chordal manner from the periphery of the disc (a workable range of the slot angle indicated as "A," is approximately from 45° to 90°) the other, or base leg 40 being at a right angle to the first leg and extending in a direction opposite to which the disc will rotate with the spindle. An edge 41 on base leg 40 is sharpened to provide a cutting edge which will function in the manner of the cutting edge 32 of the blade 30. The material of the discs 16 and 36, is preferably metal, or equivalent to provide the required strength, or rigidity.

It may be desirable to place a cutting means somewhere on the machine, i.e., not on, or associated with the discs 36, or 16, and still obtain convenient and satisfactory cutting action of the fiber after winding has begun on the core 18.

In both of the embodiments disclosed above, the legs 22 and 38 of the L-shaped slots provide an abutment means whereby one edge of the slot will engage a fiber when contact is made therewith at start of a winding operation, as will be more apparent hereinafter.

Start of a core winding operation using the device of the invention, is as follows. A moving fiber 44, is man-

ually pulled down from between the hanger means 12 so as to pass around a winder compensating arm 14, thence up between a core 18 and the pressure plate and traversing guide assembly 10 toward the right (FIG. 1) of the core. The portion of the fiber 44 below the core is held in position near the longitudinal center of the core while that portion of the fiber above the core is pulled into close proximity to the spinning disc 16. This causes the fiber to engage in the slot 22 and begin wrapping about the core 18. The free end of the fiber is then pulled across the face of the disc, which motion brings it in contact with the blade cutting edge 32 causing it to be cut. The cut, or waste end of the fiber is then released, whereupon it is drawn into a collection bag (not shown) on the outlet end of the aspirator. It should be noted that the fiber 44 is always in motion during start of a thread winding operation upon a core; in other words the machine need not be slowed down or stopped at any time during core winding.

An alternative method of starting a core winding operation, is as follows. The moving fiber 44 is manually pulled down from between the hanger means 12 so as to pass around the winder compensating arm 14, thence up between the core 18 and the pressure plate and traversing guide assembly 10 toward the left (FIG. 1) of the core, and held in position near the longitudinal center of the core 18. The fiber is pulled down across the rotating core and then outward and down to cause it to pass across the disc 16. As this is done, the fiber is caught by the slot 22 of the disc which action commences wrapping of the thread about the core. The free end of the fiber extending from the slotted disc is then pulled across the face of the disc, which motion brings the fiber into contact with the cutting edge 32 causing it to be cut. The cut, or waste end of the fiber is then released, whereupon it is drawn into a collection bag (not shown) on the outlet end of the aspirator.

It will be seen from the foregoing that the device of

the invention will satisfy the objectives set forth hereinbefore.

The foregoing description has been given in detail without thought of limitation since the inventive principles involved are capable of assuming other forms without departing from the spirit of the invention or the scope of the following claims.

What is claimed is:

1. A core winding starter for use on a thread winding machine having a spindle for receipt of a core and including, a flat circular disc arranged for attachment to the end of a spindle for rotation therewith, said disc having an L-shaped slot formed therein which extends inwardly from the periphery of the disc with the base leg of said slot extending in a direction opposite to the direction in which the disc is rotated while on the spindle, said slot being arranged for engagement of a thread when brought into contact with the disc to cause initial wrapping of the thread upon the core, and a cutting means positioned near the end of the base leg of the slot for cutting a thread after it is engaged by the slot.
2. A core winding starter according to claim 1, wherein said cutting means is formed of a blade having a cutting edge extending across said slot.
3. A core winding starter according to claim 1, wherein said cutting means is formed on the base leg of the L-shaped slot.
